ATTORNEY:

UNITED STATES PATENT OFFICE.

SAMUEL LEEDS ALLEN, OF MOORESTOWN, NEW JERSEY.

CULTIVATOR.

SPECIFICATION forming part of Letters Patent No. 712,232, dated October 28, 1902.

Application filed March 29, 1902. Serial No. 100,558. (No model.)

To all whom it may concern:

Be it known that I, SAMUEL LEEDS ALLEN, a citizen of the United States, and a resident of Moorestown, State of New Jersey, have invented certain new and useful Improvements in Cultivators, of which the following is a full, clear, and exact description, reference being had to the accompanying drawings, forming part of this specification.

10 My invention relates to improvements in cultivators of the walking type, having handle-bars for the use of the operator in working the same.

The primary object of my invention is to 15 provide a construction of cultivator having pivoted side bars and means for adjusting the same laterally to increase or diminish the width of the machine and in providing a simple and effective brace-bar for bracing the 20 center bar, side bars, and handle-bars together, thus imparting strength and rigidity to the machine, and, further, in providing an adjusting-bar for each side bar, which can be operated simply by the loosening of one bolt 25 or nut and which when secured in its adjusted position will be rigidly braced to the center bar and handle-bars of the machine.

I am aware that braces have been used heretofore for bracing the side-bar-spreading 30 mechanisms to the handle-bars and that it is a common expedient to brace the handle-bars to the center bar—such, for instance, as shown in some of my former patents and in a number of others; but in most of these constructions the brace-bar which connects with the 35 spreading mechanism would be subjected to great strains during the adjustment and require an adjustable connection with the handle-bars, thus necessitating the unloosening 40 of two or more bolts before the adjustment could be effected.

In my prior patent, also in some other existing patents, the brace-bar is connected to the spreading mechanism, which, being movable, requires a compromise or harmony of motion between the brace and the expanding device, thus causing an imperfect result, because the parts working from opposite or different centers force the result and distort the 45 tool.

In my present construction the brace is not attached to the expanding device; but it is

either bolted directly to an arm rigidly attached at substantially right angles to the middle bar by riveting or bolting or is made 55 of one piece with said arm, and the expanding device slides directly beneath the single piece or between the two pieces described, making a very firm connection without extra bolts. A further advantage of such a construction resides in the fact that one side can be adjusted independently of the other, as sometimes it is desirable to have one of the side bars opened wide and the other one partially closed. It will thus be seen that in my 65 present construction I have provided a brace which is positively rigid, having a rigid connection to the center bar and a rigid connection with the adjusting-bar for the side arms, so that the machine is exceeding strong and 70 firmly braced after the adjustment has been made.

In the accompanying drawings, Figure 1 is a plan view of a cultivator constructed in accordance with my invention. Fig. 2 is a side 75 elevation of the same. Fig. 3 is a detail view showing the brace in end elevation, and Fig. 4 is a similar view showing a slightly-modified construction of brace.

Referring to the said drawings, A designates the center bar of a cultivator, having the side bars B and C pivoted thereto through the medium of the clevis D, which is secured to said center bar at its forward end.

To the rear ends of the side bars B and C 85 are pivoted the adjusting-bars E, each provided, preferably, with the longitudinal slots F, through which passes the bolt G, which is carried by the brace-bars H and I. An even stronger combination is obtained by substituting a series of holes in the expanding-bars in place of the slots; but this construction renders the adjustment more difficult. The bars H are preferably disposed transversely to the center bar A and are rigidly secured 90 thereto by means of the bolt J. The bolt G passes through an aperture provided in the free end of the bar H and through the slot F in the adjusting-bar E and through a foot provided on the end of the inclined brace I 100 and is held in position by means of a suitable nut, as K. The brace I is rigidly secured at its upper end to the handle-bar L, so that it is held positively rigid at all times. The han-

dle-bars L are secured at their forward ends to the center bar A in the usual manner and are provided at the upper ends with the connecting brace rod or round M of the usual 5 form.

When it is desired to adjust the width of the machine, all that is necessary is to loosen up the nut K on bolt G and then move the side bars in or out, the bolt, which passes 10 through the slot F in the bars E, serving to guide said bar, and when the end of the slot is reached the bar E can be swung around with the bolt G, acting as a pivot, and thus bring the side bars as close to the center bar 15 as possible. When the desired adjustment is effected, the nut K is again tightened, thereby rigidly connecting the three bars E, H, and I and insuring a rigid connection with the handle-bars, thus rendering the machine perfectly rigid, strong, and durable during its working operation.

It will thus be seen that the brace I is positively rigid against movement at all times, it being rigidly fastened at both ends, its lower 25 end being secured against movement by reason of its connection with the rigid brace-bar H through the medium of the bolt G, so that during the adjusting operation the said bar I is relieved of strain and cannot be twisted or bent out of shape, and thus weakened, as is the case with most braces which have a connection with the side-bar-spreading mechanism.

Another advantage in a construction of this 35 kind is its simplicity and consequent cheapness of cost to manufacture, also in the fact that it is necessary only to loosen one bolt—viz., the bolt G—in order to effect the adjustment of the width of the machine.

40 In Fig. 4 of the drawings I have shown the brace-bars H and I as integral, and the adjusting-bar E in this construction is secured to the under side of the section H and operates in substantially the same manner as 45 heretofore described. The first-described construction is slightly preferable, because the spreading-bar G is in that construction confined between the ends of the two braces H and I, as shown most clearly in Fig. 3, and 50 thus further braced against any twisting movement to which the said bar might be subjected.

Having thus described my invention, what I claim, and desire to secure by Letters Patent, is—

55 1. In a cultivator, the combination with the

center bar having pivoted side bars and handle-bars carried by the center bar, of a rigid brace extending from the center bar and connecting with the handle-bars, and an adjusting-bar connected to the side bars and to the rigid brace, for the purpose described. 60

2. In a cultivator, a central frame-bar, side bars pivotally secured thereto, handle-bars secured to the central bar, a rigid brace-arm 65 secured to the central bar extending transversely thereto, a rigid brace-arm connecting with the transverse arm and rigidly secured at its upper end to the handle-bar, and a connection between the side bars and the rigid 70 transverse arms, substantially as described.

3. In combination, a central bar, side bars pivoted thereto, handle-bars secured to the central bar, adjustable connections between the side bars and the central bar, rigid arms 75 extending from each side of the central bar, and brace-bars rigidly secured at one end to the handle-bar and at its other end to rigid arms of the central bar, substantially as described. 80

4. In combination, a central bar, side bars pivoted thereto, handle-bars secured to the central bar, rigid arms extending from each side of the central bar, a spreading-bar adjustably secured to one of the said rigid arms 85 and pivotally connected at its other end to the side bars, and a rigid brace secured to the handle-bar and to the rigid transverse arm, said brace being positively secured against movement, for the purpose substantially as 90 described.

5. The combination of a central bar, side bar pivoted to said central bar, handle-bars secured to the central bar, transversely-disposed arms rigidly secured to the central bar 95 and extending under the handle-bars, rigid braces secured to the handle-bars at one end and to the transverse arms at their lower ends, spreading-bars pivoted at one end to the side bars, having their other ends clamped 100 between the rigid brace and the rigid transverse arm, and a longitudinal slot provided in said spreading-bars adapted to receive the clamping-bolt which connects the two rigid brace-bars, substantially as described. 105

In witness whereof I have hereunto set my hand this 22d day of March, A. D. 1902.

SAMUEL LEEDS ALLEN.
